SUCTION CLEANER

Warren V. Prince, North Canton, Ohio, assignor
to The Hoover Company, North Canton, Ohio,
a corporation of Ohio

Application December 17, 1938, Serial No. 246,311

19 Claims. (Cl. 15—8)

The present invention relates to suction cleaners in general and particularly to a new and novel rotary agitator for a suction cleaner. More specifically the invention comprises a rotary agitator for a suction cleaner which includes agitating elements subject to wear in use in combination with automatic means which adjust the agitating elements to compensate for such wear.

It is an object of the present invention to provide a new and improved suction cleaner. It is another object of the invention to provide a new and improved rotary agitator for a suction cleaner. A further object of the invention is to provide a new and improved rotary agitator embodying automatically adjustable agitating elements. A still further object of the invention is to provide a rotary agitator for a suction cleaner which embodies flexible brush elements subject to wear in use in combination with automatically functioning means which re-position the brush when necessary to compensate for wear. Still another object of the invention is to provide a rotary agitator for a suction cleaner which embodies agitating elements subject to wear and decrease in size with use, and which includes automatic means positioned wholly within the normal agitator body when the agitator is in use, which functions to re-position the agitating element to compensate for wear therein when required. Still another object of the invention is to provide automatic means which measure the brush extension and re-position the brush when its radial extent has been reduced by wear. A still further object of the invention is to provide a rotary agitator comprising a cylindrical body in which are seated flexible brush elements subject to wear with use and automatic means to re-position the brush elements radially when their extension has been decreased because of said use, the automatic means being positioned wholly within the agitator body in operation. These and other more specific objects will appear upon reading the following specification and claims and upon considering in connection therewith the attached drawings to which they relate.

Referring now to the drawings in which a preferred embodiment of the present invention is illustrated:

Figure 1 illustrates a front view of a suction cleaner of modern design in which an agitator constructed in accordance with the present invention is embodied;

Figure 2 is a partial longitudinal section upon the line 2—2 of Figure 3 through the agitator comprising the present invention and illustrates

the brush positioned in the agitator body and the automatic means by which the brush is re-positioned:

Figure 3 is a transverse section upon the line 3—3 of Figure 2 and illustrates the relationship of parts with the agitator rotating;

Figure 4 is a section on the line 4—4 of Figure 2 and discloses the position of the parts with the agitator at rest;

Figure 5 is a section upon the line 5—5 of Figure 2 and shows the spring means which normally urge the brush radially outward;

Figure 6 is a transverse section through the agitator and illustrates the relative position of the parts in their running position and with a worn brush in the agitator which has been previously adjusted to its final and last radial position;

Figure 7 is a section similar to Figure 4 and illustrates the mechanism re-setting operation.

The rotary agitator of the modern suction cleaner comprises a cylindrical body upon the surface of which are positioned rigid beating elements and in which are mounted flexible brushing elements. In cleaner operation the surface covering undergoing cleaning is lifted within the orbit described by the rotation of the brushing and beating elements and receives from the rigid beating elements a positive vibration and from the flexible brushing elements a pile straightening and litter removing action. The rigid beating elements of the agitator are made of hard polished metal which does not decrease in size or radial extension throughout the life of the agitator. The flexible brush elements, however, are normally made of animal hairs which do wear away with use. As the brush extension decreases a point is reached at which the brush no longer functions to perform its agitating effect and unless the brush is readjusted to the proper radial extension, which comprises substantially the same extension as the rigid beating elements, or a slightly greater extension, the agitator functions solely as a rigid beater agitator.

In recognition of this condition agitators in the past have been made with removable brush elements and with manually adjustable elements. The removable elements were adapted to be replaced by new elements which would have the proper radial extension, while the manually adjustable elements were adapted to be repositioned in the agitator by the operator to give a greater radial extension to a worn brush. Both types are subject to the serious objection that the usual cleaner operator is not a skilled mechanic and

does not closely observe the cleaner action, and as a result the agitator frequently functions for long periods of time in an inefficient condition.

In the agitator constructed in accordance with the present invention the flexible brush elements which are subject to wear are combined with means which automatically gauge their radial extension and, when that extension has been decreased below a certain point, the adjustment automatically moves the brush radially outward to the proper extension. The means by which this adjustment is accomplished is positioned entirely within the normal periphery of the agitator body in the operation of the agitator and accidental brush adjustment cannot occur.

Referring again to the drawings, and to Figure 1 in particular, a modern suction cleaner is illustrated which embodies the usual parts of a suction cleaner including a nozzle 1 which is connected in the usual manner to a fan chamber 2 which houses a suction-creating fan 3 driven by an unshown motor positioned thereabove within the motor housing 4. The motor shaft 5 extends downwardly through the fan chamber 2 into the air passageway 6 which interiorly connects the fan chamber 2 to the nozzle 1 and, through a power-transmitting belt 7, rotates the rotary agitator 8 which comprises the present invention. The cleaner is movably supported upon wheels 9 and, as in the usual cleaner, a pivoted handle 10 is provided by which the operator can exert a propelling force.

Referring now to Figures 2 to 7, inclusive, the agitator per se of the present invention is clearly illustrated. It is seen to comprise an elongated cylindrical body 12 formed substantially centrally with a grooved pulley portion 13 and with its ends closed by end plates 14 which are centrally cupped to seat a bearing 15 the inner race of which is supported by an elongated shaft 16 extending the length of the agitator and from the ends thereof. A thread guard 17 is threaded upon each end of the shaft 16 and overlaps the agitator end to provide a protection for the bearing 15 adjacent thereto.

Helically extending rigid beater bars 18 are positioned upon the periphery of the agitator body 12 and extend from substantially common end points on the agitator in a common and well known manner. These beating elements 18 also extend radially beyond the agitator body 12 and are adapted to contact a surface covering undergoing cleaning which is lifted by the nozzle suction. Cooperating with the rigid beating elements 18 are brushes 19 which are axially extended and each of which comprises a rigid back 20 in which are mounted a series of brush tufts 21. Brushes 19 are positioned within brush seats 22 formed interiorly of the agitator body 12, the side walls of the brush seats 22 being spaced from the brush tufts 21 which extend radially beyond the normal periphery of body 12 to a distance substantially equal to the radial extension of the rigid beater elements 18.

It is the brush elements 19 which are subject to wear in use and to provide for this wear and to compensate therefor brush adjusting means are provided within the agitator body. The brush adjusting mechanism includes a brush carrier 24 which is a plate like member extending parallel to the bottom of the brush seat 22, provided at its ends with axially projecting pins 25 which extend beyond the ends of the brush seat 22. The back 20 of the brush is remov-

ably secured to the carrier 24 by manually removable screws 26.

Positioned immediately adjacent each end wall of each brush seat 22, and rotatably mounted upon an elongated pin 27, is a rotatable cam 28 formed in its periphery with a plurality of seats 29 for the pin 27. The pin 27 at each end of the brush carrier 24 is pressed against the adjacent cam 28 by the action of a pair of curved leaf springs 30 which are carried by the interior of the agitator body 12 and which extend into the brush seat 22 to contact the underside of the brush carrier 24 to urge that member, together with the brush carried thereby, radially outward.

The radial position of the brush in the seat is determined by the radial position of the brush carrier which is itself dependent upon the contact of its pins 27 with the cams 28. Pairs of pin seats 29 in the cams at the opposite ends of each brush seat are at the same radial distance from the axis of cam rotation, comprising the elongated pin 27, and each pair is at a lesser radial distance advancing clockwise around the cams as viewed in Figures 3 and 4. It is clear that by the rotation of the cam at each end of the brush seat the brush carrier pin 27 can be advanced from one pin seat 29 to an adjacent pin seat to give the brush carrier and the carried brush a greater radial extension.

The determination that the brush element should be adjusted radially to compensate for brush wear is accomplished by an elongated trigger or feeler 32 which extends the length of the brush and which includes side arms 33 at its end which are pivoted substantially midway of their length upon the elongated pins 27. At their inner ends the arms 33 are connected by and carry a counterweight 34 which, in the rotation of the agitator at its normal speed, exerts a centrifugal force which overcomes the weight of the trigger 32 and withdraws it radially inward; the counterweight 34 in this movement also acts against the pressure exerted by the coil spring 35 mounted on the outer pin 27 of each brush seat. With the agitator standing, however, the force of the spring 35, which at one of its ends contacts a rigid shoulder 36 formed on the brush seat, and at its opposite end contacts the trigger arm 33, moves the curved pivoted trigger 32 radially outward through a slot provided therefor in the agitator body until the trigger bears against the side of the brush tufts 21 at their extremities. If the tufts are of proper length trigger 32 contacts the side thereof and has its pivotal movement limited to the dotted line position illustrated in Figure 3. If, however, the brush bristle length has been decreased by wear so that the trigger member is able to slide over the top thereof, as illustrated in Figure 4, then the trigger 32 pivots through a greater angle under the urging of the coil spring 35 to the position illustrated in Figure 4. It is this difference in the angularity assumed by the trigger 32 with the agitator at rest under the two conditions just described that indicates the need for, or the absence of the need for, adjustment of the brush.

To utilize this variation in feeler or trigger angularity to accomplish brush adjustment, there is provided a ratchet wheel 37 upon the pin 27 which ratchet is fixed to the cam 28 for conjoint rotation therewith. Ratchet 37 is provided with peripheral teeth 38 the angular arrangement and spacing of which conforms to

that of the seats 29 upon the cam 28. Cooperating with the ratchet 37 is a pivoted pawl 40 upon each side arm 33 of the trigger 32 which pawl is pressed into contact with the ratchet by a coil spring 41 enclosing the pivot pin 42 upon which the pawl is pivoted. The ratchet and pawl construction at each end of each brush seat is identical.

The operation of the brush adjustment constructed in accordance with the present invention is as follows:

With a new full length brush in the agitator the brush and its carrier 24 will be positioned at the innermost radial position in the brush seat 22. Each brush positioning cam 28 will be so positioned that its seat 29 at the greatest radial distance from its rotational axis, comprising the pin 27, is in contact with the brush carrier pin 25. This relationship will exist at each end of the brush seat. With the agitator rotating the relationship of parts will be as illustrated in Figure 3 and it is to be noted that the counterweight 34 acting through its supporting arm 33 has pivoted the feeler or trigger 32 inwardly into the agitator body.

Upon the cleaner being placed out of operation the rotation of the agitator ceases and immediately, under the pivoting action of the coil springs 35, each trigger 32 moves outwardly through the agitator body and contacts the side of the brush tufts 21 throughout the length of the brush 19. With the brush new the radial extension will be such that the trigger will, as stated, contact the side of the brush tufts, as illustrated in dotted lines in Figure 3, and the pivotal movement of the trigger 32 and the arms 33 will not be sufficient to permit the spring pressed pawl 40 at each end of the brush to move into contact with the second tooth 38 of the ratchet 37. When the cleaner is again placed in operation and the centrifugal weight 34 swings the trigger unit in a counterclockwise direction as viewed in Figure 3 to withdraw the trigger into the agitator body, the pawl 40 will merely slide along the ratchet 37 back to the first tooth 38 and no rotation of the ratchet or the cam 28 connected thereto will take place.

After the cleaner has been used for a considerable period of time, however, the brush bristle length has decreased and upon the agitator being stopped and the trigger being pivoted outwardly under the spring force of the spring 35, the trigger will pass beyond the side of the brush tufts, its "new brush" position being illustrated in dotted lines in Figure 3, and will extend over the brush, as illustrated in the "worn brush" position in Figure 4. This greater angular movement of the trigger unit is sufficient to permit the pawl 40 to slide into contact with the second tooth of the ratchet 37 so that when the agitator is again rotated and the trigger unit pivoted under the centrifugal force exerted by the counterweight 34 the pawl 40 will cause the ratchet 37 to rotate in a counterclockwise direction so that the second cam seat 29 is brought into contact with the brush carrier pin 25. The leaf springs 30 through urging the brush carrier and the carried brush radially outward will urge the pin 25 against this new seat of the cam which will result in the agitator brush being positioned at a greater radial distance and with a greater radial extension.

The identical action takes place at each end of each brush so that the two ends are simultaneously adjusted.

The above described adjustment will repeat to a number determined by the design, the exact number of adjustments not being of the essence of the invention. After the final adjustment has been made, however, and the brush has continued to be used so that a further adjustment is required in order to obtain effective brushing, it is necessary to replace the worn out brush by a new brush and to reset the positioning mechanism.

10 This substitution of a new brush and the re-positioning of the adjusting mechanism is a simple operation. The operator, by the use of a screw driver removes the brush-securing screws 26 and substitutes for the worn out brush 19 a new brush having full length bristle tufts 21. The operator then pivots inwardly into the agitator body the curved feeler member 32 and uncovers near each end of the brush a small screw 44 which forms a part of the agitator construction adjacent the adjusting mechanism. These screws he removes by the same screw driver with which he secured the new brush in place and upon their removal small apertures are provided into the interior of the agitator body, as illustrated in Figure 7. Through each of these apertures a small tool 45 is inserted which passes downwardly and into contact with a notch 46 formed upon the pawl 40. Sufficient force is exerted upon the tool 45 to overcome the force of spring 41 acting upon the pawl and to pivot it from the ratchet 37. While holding the pawls in this displaced position the operator then exerts an inward radial force upon the new brush for the purpose of moving the brush carrier pins 25 downwardly from contact with the cam 28. With the pins 25 removed from the cams 28 and with the pawls 40 out of contact with the ratchets 37, each ratchet cam unit 31, 28 pivots in a clockwise direction, as viewed in Figures 3, 4 and 7, under 20 the action of a small spring 48 which seats upon the elongated pin 21 adjacent the principal coil spring 35. One end of this small spring abuts against the agitator body while the other end contacts the ratchet-cam unit. The ratchet-cam unit is rotated until the cam 28 contacts the pin 25 which is positioned by the brush carrier being held to the bottom of the brush seat. The operator then releases the brush which is then forced radially outward by the flat springs 30 so that the pins 25 seat against the new brush seat 29 in the cam. The tool 45 is then withdrawn and the agitator upon being re-inserted into the cleaner nozzle in the proper relationship is ready for use.

55 I claim:

1. A rotary agitator for a suction cleaner or the like including an agitating element subject to wear in use, means automatically to adjust said element radially to compensate for wear including a gauge to measure the radial extension of said element and to control said adjusting means, and means to rotatably support said element and said adjustment means.

65 2. A rotary agitator for a suction cleaner or the like including an agitating element subject to wear in use, means automatically to adjust said element radially to compensate for wear including means to move said element radially upon the rotation of the agitator and a gauge to measure the radial extension of said element with the agitator at rest and to control said moving means, and means to rotatably support said element and said adjustment means.

70 3. In a rotary agitator for a suction cleaner or the like, a rotatable body, an agitating ele-

ment subject to wear with use mounted in said body and movable radially relative thereto, a gauge element normally positioned within said body during the rotation thereof and movable to measure the radial extension of said agitating element with the agitator standing, and means to return said gauge element to within said body upon the rotation thereof and to adjust said brush radially according to the findings of said gauge element.

4. In a rotary agitator for a suction cleaner or the like, a rotatable body, a brush element seated in said body and including bristles extended radially therebeyond, a step-by-step adjustment to move said brush radially outward, and a gauge element movably mounted within said body to measure the radial extension of said element and operatively connected to and adapted to control said step-by-step adjustment.

5. In a rotary agitator for a suction cleaner or the like, a rotatable hollow body, a radially movable brush mounted in said body, and means to adjust said brush radially automatically to compensate for wear including: a brush carrier, cam means determining the radial position of said carrier, agitator-rotation-operated means to adjust said carrier radially and a gauge to determine the radial extension of said brush by contact therewith and to control said agitator-rotation-operated means.

6. In a rotary agitator for a suction cleaner or the like, a rotatable hollow body, a radially movable brush mounted in said body, and means to adjust said brush radially automatically to compensate for wear including: a brush carrier, a rotatable cam controlling the radial position of said carrier in said body, a ratchet secured to and rotatable on said cam, a pawl to rotate said ratchet, a trigger to contact the extremity of said brush and to advance said pawl relative to said ratchet upon a predetermined decrease in the radial extension of said brush, and centrifugal means to withdraw said trigger within said body and to exert a ratchet-rotating force through said pawl upon the rotation of said agitator to rotate said cam.

7. In a rotary agitator for a suction cleaner or the like, a rotatable hollow body, a radially movable brush mounted in said body, and means to adjust said brush radially automatically to compensate for wear including: a brush carrier, a rotatable cam controlling the radial position of said carrier, a step-by-step adjustment to rotate said cam, a gauge to determine the radial extension of said brush element and to set said step-by-step adjustment for operation upon a predetermined decrease in the radial extension of said brush, and means to actuate said step-by-step adjustment.

8. In a rotary agitator for a suction cleaner or similar device, a rotatable body, a brush element carried by said body and subject to decrease in radial extension with wear in use, a gauge extended beyond said body when standing and having its position determined by the extension of said brush element, means to adjust said brush element radially operatively positioned by the movement of said gauge to a "worn-brush" position, and means to withdraw said gauge within said body and to actuate said adjustment means upon the rotation of said agitator.

9. In a rotary agitator for a suction cleaner, an agitating element subject to decrease in size with wear, means rotatably supporting said element, means automatically to gauge the radial

extension of said element, and means controlled by said gauge automatically to adjust said element radially after said gauge determines a "worn-brush" condition.

5 10. In a rotary agitator for a suction cleaner, an agitating element subject to decrease in size with wear, means rotatably supporting said element, automatic means to measure the radial extension of said element in a non-rotating condition, and centrifugally operated means controlled by said gauge automatically to adjust said brush upon rotation and upon said gauge determining a "worn-brush" condition.

11. In a rotary agitator for a suction cleaner, 15 a rotatable body, a brush seated in said body and extended radially therebeyond, a gauge in said body, means to project said gauge through said body to determine the radial extension of said brush with the agitator standing, means to move 20 said brush radially controlled by said gauge, and centrifugal means operative upon the rotation of the agitator to withdraw said gauge within said body and to actuate said brush moving means.

12. A rotary agitator for a suction cleaner including a rotatable body, a brush element subject to wear in use, a gauge carried by said body to determine by direct measurement the presence or absence of a proper brush adjustment, means to move said brush including parts positioned by 30 said gauge, and means to operate said means to adjust said last-mentioned brush.

13. In a rotary agitator for suction cleaners, a brush element subject to decrease in radial extension with use, and means to adjust said 35 element radially to compensate for wear including means controlled directly by the radial extension of said element.

14. A unitary removable rotary agitator for suction cleaners comprising the following, an 40 agitating element subject to decrease in size with use, means to detect the decrease in size of said agitating element to a predetermined limit by direct measurement, and means operative only after said first-mentioned means detects a decrease in size to said predetermined limit to adjust said element relative to the axis of rotation to compensate therefor.

15. In a rotary agitator for a suction cleaner, an agitating element subject to decrease in 50 radial extension with use, means to measure the radial extension of said element upon said agitator coming to rest following rotation, means to move said element radially outwardly controlled by said measuring means, and means to move 55 said measuring means to inoperative position and to actuate said element moving means upon rotation, the latter being effective to adjust said element radially under the control of said measuring means.

60 16. A rotary agitator for a suction cleaner comprising a rotatable hollow cylindrical body, a brush movable radially relative to the axis of rotation of said body, means to move said brush radially outward including a centrifugally operated element movable between a brush adjustment position and a second position, gauge means to determine the radial extension of said brush and controlling the movement of said centrifugally operated element into its brush adjustment 65 position, said gauge means placing said centrifugally operated element in brush adjustment position upon determining a predetermined decrease in radial extension of said brush.

75 17. A rotary agitator for a suction cleaner comprising a rotatable hollow cylindrical body, a

brush seat in said body, cam means controlling the radial position of said brush in said seat, a step-by-step adjustment controlling the position of said cam and including a movable element, a feeler operative upon said agitator stopping rotation mounted in said body and movable there-through into contact with the extremity of said brush with optimum brush extension and adapted to move over said brush with said brush at a lesser extension, said feeler controlling the movement of said movable element to a position for adjustment operation, spring means urging said feeler outwardly to brush-contacting position and centrifugal means to move said feeler and said movable element to operate said step-by-step adjustment.

18. In a rotary agitator for a suction cleaner, a rotatable body, a brush seated in said body and extended radially therebeyond, a gauge in said body, means to project said gauge through said body to determine the radial extension of said brush with the agitator standing, means to move said brush radially step-by-step controlled by said gauge, centrifugal means operative upon the rota-

tion of the agitator to withdraw said gauge within said body and to actuate said brush moving means, characterized by the fact that said rotatable body is provided with an aperture adapted to receive a tool to re-set said brush-moving means.

19. In a rotary agitator for a suction cleaner, a hollow rotatable body, a brush seated in said body and radially adjustable, and means to measure the radial extension of said brush and 10 to adjust said brush including: a brush carrier, a cam to advance said carrier radially, a ratchet connected to said carrier to actuate same, a spring-pressed pawl operatively associated with said ratchet to actuate same, a brush gauge 15 carrying said pawl and movable to determine the radial extension of said brush, and agitator-rotation-operated means to move said gauge to inoperative position and to move said pawl relative to said ratchet, characterized in that when 20 said gauge determines a brush extension below a predetermined point said pawl is advanced relative to said ratchet.

WARREN V. PRINCE.

CERTIFICATE OF CORRECTION.

Patent No. 2,281,798.

May 5, 1942.

WARREN V. PRINCE.

It is hereby certified that error appears in the printed specification of the above numbered patent requiring correction as follows: Page 4, second column, line 31, claim 12, strike out "last-mentioned" and insert the same after "said" and before "means" in line 30, same claim; and that the said Letters Patent should be read with this correction therein that the same may conform to the record of the case in the Patent Office.

Signed and sealed this 14th day of July, A. D. 1942.
